BURNER

Joseph C. Williams, Kansas City, Mo.

Application August 29, 1932, Serial No. 630,764

3 Claims. (Cl. 158—73)

This invention relates to oil burner systems used in heating plants of different types, and has for its primary object the provision of such a system wherein is incorporated unique members and parts, all of which combine to create a more efficient, effective and novel heating plant.

A further object of the invention is to provide, in an oil burner system, means for automatically controlling the supply of water and gas or other substances through the medium of the expansibility of a portion of the conduits built into the system.

A still further object of the instant invention is the provision of unique, novel, and improved steam generating and burner-head members, each of which forms an important part of the system and is created to present exceptionally efficient, strong and durable parts for a system employing steam oil and air as a fuel medium.

An additional aim of this invention is to provide a burner-head having means for deflecting and guiding the flame back upon itself to a point where it reaches the original point of exit from the tubular portion of the burner-head.

These and many more important objects will be referred to in the accompanying drawings, wherein:

Figure 1 is a broken, side elevation of a hot air heating plant having an oil burner system therein embodying the features of this invention.

Fig. 2 is an enlarged, vertical, central section through the burner-head of the system.

Fig. 3 is a fragmentary, vertical section of the burner-head taken on line III—III of Fig. 2.

Fig. 4 is a vertical, central section through the steam generator employed in the system.

Fig. 5 is a vertical, longitudinal section through the expansible length of conduit used in actuating certain valves.

Fig. 6 is an enlarged, detailed, plan view of the nozzle forming a part of the burner-head, and,

Fig. 7 is a vertical, central section through the nozzle, taken on line VII—VII of Fig. 6.

The parts of the burner system contemplated by this invention might be used in any type of heating plant, and in the instance illustrated, the same is installed in an ordinary hot air furnace 10 having the customary fire box 12 that is reached through the entrance 14 thereto.

Steam is used in atomizing the supply of oil to the hereinafter described burner-head, and when this system is put into use, the hollow, spherical body 16 of the steam generator 18 is supplied with water from the service mains to pipe 20 which leads to a suitable filter 22, from

whence it travels to valve 24 through the pipe 26 having a pressure reducing valve 28 therein, and further having in communication therewith a compensating tank 30 to maintain a substantially uniform pressure, from this point water passes to body 16 through pipe 32. Valve 24 is always slightly open and when starting the system, manually operable valve 34, interposed in pipe 32, is opened to allow water to pass into body 16. A burner 36, positioned below body 16, is supplied with gas through pipe 38 and the water first introduced to body 16 is converted to steam.

Pipe 38 has a valve 40 therein which must be opened when lighting burner 36 because the thermostatically controlled valve 42 in this pipe is always slightly open. Generator 18 is novelly constructed, as illustrated in Fig. 4, to the extent that pipe 32 extends therewith and is circumscribed by burner 36 which is held in spaced relation to pipe 32 by connections 44 that combine to create a clean-out passage for body 16.

These connections 44 lead to a point where a receptacle may be placed thereunder and when valve 46 is opened the contents of body 16 will flow therefrom and the interior of the body may be flushed as much as desired, and under a head of steam if needed.

After burner 36 has been lighted and water supplied to generator 18 as mentioned, steam is created which escapes through pipe 48 leading to a point exteriorly of furnace 10. This pipe 48 joins connection 50 which is anchored by fixture 52 to a part of furnace 10. A pressure gauge 54 is mounted on connection 50 to indicate the steam pressure and since it is the object to introduce steam to the burner-head of the system, pipe 48 is continued to the atomizer of the burner-head by an expansible length of pipe 56 and another pipe 58. Pipes 56 and 58 are joined by specially formed elbow 60 having arms 62 and 64 that operably engage valves 24 and 42 respectively. Thus, as steam passes through the steam pipe from generator to atomizer, expansible length 56 thereof will lengthen and elbow 60 will be moved from fixture 52. When the length 56 contracts as a result of a lesser amount or no steam passing through link 56, elbow 60 will move back toward fixture 52. As steam expands length 56, valve 24 will be opened to allow the entrance of additional water to the generator. Also, as pipe 56 expands, valve 42, which supplies gas to burner 36, will be closed and when the system is under way, length 56 will be expanded to its maximum capacity; valve 42 will be closed, and

heat for generator 18 will be supplied thereto by burner-head 66.

As soon as sufficient steam is generated, valve 68 in oil conduit 70 will be opened to permit the 5 passage of the fuel oil to atomizer 12, disposed at the lower portion of the burner-head 66. The oil and steam are thrown together immediately above atomizer 12 in a unique fashion because of the formation of atomizer 12, air being introduced into the mixture at intake 96 just prior to ignition.

As shown in Figs. 6 and 7, this atomizer has a vertical, centrally disposed oil outlet port 74 which extends through nipple 76 and member 15 78 which is in connection with pipe 70. Steam from pipe 58 enters atomizer 78 below nipple 76 and is expelled upwardly through exit ducts 80 formed through nipple 76, as illustrated in Fig. 7. These exit ducts converge as the upper outlet 20 end is approached. Lines projecting longitudinally from these ducts will intersect the projected vertical, longitudinal line of port 74 at a point above nipple 76. Thus a complete atomization takes place and combustion occurs immediately 25 within the tubular exit passage 82 of head 84. Head 84 is supported by casting 86 above atomizer 72 and within the fire box proper of furnace 10. The remaining portion of the burner-head should be positioned as illustrated in Fig. 1.

30 The tubular exit passage has an arch 88 formed thereover to present arcuate deflecting faces 90 which extend from the upper portion of arch 88 to a point where it joins the tubular portion of the head which forms exit passage 82. A depending, transverse ridge 92 extends across arch 35 88 and presents its edge 94 on the longitudinal center line of passage 82. Thus, when flames pass upwardly into arch 88 they are divided and sent back toward the ignition point which is just 40 below the upper edge of exit passage 82. In this manner the force of the combustion itself causes flames created thereby to positively assure ignition immediately after atomization and mixing with the proper amount of air at intake 96.

45 As shown in Fig. 2, there are two identically formed arcuate faces 90, one on each side of ridge 92, and while flames are directed back toward exit passage 82 on two sides thereof, they are permitted to escape from beneath arch 88 at the 50 two opposite sides. The overflow basin 98 is positioned below atomizer 72 and the usual drain pipe 100 leads therefrom to any suitable automatic cutoff, not here shown.

55 Specific structures of the various parts of this system have been made clear during the speci-

fication and the mode of operation and novel features have been set forth as description took place. It is understood that such modifications as fall within the scope of the appended claims and spirit of the invention might be practiced 5 without departing therefrom.

Having thus described the invention, what is claimed as new and desired to be secured by Letters Patent is:

1. In a burner head, the combination of an 10 oil atomizer, a combustion chamber comprising a deflector body having a tubular exit passage formed therethrough in alignment with said atomizer; an arch over one end of the said passage and in spaced relation to said end, the said 15 arch forming a transverse passage through said deflector body intersecting the said exit passage and open at each end; and said arch having a transverse ridge across the inner face thereof in opposed relation with said atomizer, said deflector body being supported in spaced relation 20 to the atomizer whereby the oil is projected into the combustion chamber through deflected burning gases.

2. In an oil burner system, the combination 25 with an oil atomizer, of a deflector having a tubular exit passage formed therethrough in alignment with the atomizer; an arch over one end of the exit passage and in spaced relation thereto, said arch being open at the opposed sides 30 thereof whereby to permit the escape of burning gases from therebeneath after passing from the exit passage; and a depending, transverse ridge formed across the inner side of the arch, said deflector having a concave face formed on the 35 inner side on each side respectively of said ridge, said concave faces extending from the ridge to said exit passage.

3. In an oil burner system, the combination 40 with an oil atomizer, of a deflector having a tubular exit passage formed therethrough; an arch over one end of the exit passage, said arch being open at the opposed sides thereof to permit the escape of burning gases from therebeneath after 45 passing from the exit passage; and a depending transverse ridge formed across the inner side of the arch, said deflector having a concave face formed on the inner side on each side respectively of said ridge, said concave faces extending from the said ridge to said exit passage, said ridge being V-shaped in cross section and having the edge thereof on the projected longitudinal center line of the exit passage and said atomizer. 50

JOSEPH C. WILLIAMS. 55
